UNITED STATES PATENT OFFICE.

EDOARDO FERRARA, OF MILAN, ITALY, ASSIGNOR TO SECONDO SACERDOTE, OF MILAN, ITALY.

SHIELD FOR WORKMEN.

1,265,764.

Specification of Letters Patent. Patented May 14, 1918.

Application filed August 5, 1915. Serial No. 43,873.

To all whom it may concern:

Be it known that I, EDOARDO FERRARA, a subject of the King of Italy, residing at 24 Via Solferino, Milan, Italy, have invented 5 new and useful Improvements in Shields for Workmen, of which the following is a specification.

The present invention relates to a shield for the protection of the eyes of laborers 10 that work with machinery, such as lathes, planing machines, emery polishers and others that throw off particles from the operating members or tools of the machine, or of the material acted on.

15 In order to protect the face, and particularly the eyes, of laborers that work around these machines, there are generally employed spectacles, which protect only in part the eyes and a part of the face, and which 20 besides being irksome to wear, cannot be transferred from one workman to another, for hygienic reasons.

The present invention is intended to furnish protection for the eyes and face of lathe 25 operators, engine fitters, sawyers, stone cutters, and others that have to look after machines of the class above mentioned, liable to produce and throw off shavings and other particles of material during treatment, such 30 as metals, wood, stone, and emery.

While this device assures complete protection, it leaves the workman free in his every movement, without danger of the face being injured, and without danger of transmitting dirt or disease when transferring 35 the arrangement from one workman to another, the construction being such that, as contrary to the old construction, the shield does not come into immediate contact with 40 the body of the wearer and such that it can be easily disinfected. The invention is represented, by way of example, in the drawing hereto annexed, in which;

Figure 1 is a side elevation of the improved shield; and,

Fig. 2 is a front elevation of the same.

The shield consists of a frame of rectangular form *a*, containing in its upper part a transparent medium such as a glass panel *b*, 50 and in the lower part thereof a metallic net work *c* in a way that, while the transparent portion or panel protects the eyes and a part

of the forehead, the net work, in its turn, protects the lower parts of the face, the nose, the mouth, etc. An extension *q*, in addition, 55 hangs loosely over the chest and thus protects this part of the body from the sparks or other particles which may be thrown toward the operator or workman. Two metallic screens *d*, placed at the sides, serve to 60 protect the temples and to deflect the particles from the sides of the head. The parts *c* and *q*, being constructed of metallic cloth, that is, wire mesh, may be easily disinfected by exposure thereof to a flame or otherwise. 65

Attached to the frame *a* are metallic bands *e*. These bands are connected near their lower ends by a cross-piece *f* which serves to rigidify the structure. The bands *e* may be readily bent as may be necessary, by hand, 70 in order to adapt them to the shoulders of large or small workmen, thus rendering each shield within a certain limit of sizes, adaptable to several workmen. To the extremities of the bands *e*, small straps *g* and 75 buckles *h* are attached, which may be passed under the arm-pits and connected by buckling, sufficient adjustment being permitted to tightly secure the guard to the body.

Having thus particularly described my invention, what I claim as new and desire to secure by Letters-Patent of the United States of America is:

A shield comprising a rigid rectangular 85 frame, a transparent medium occupying a portion of said frame, flexible foraminous material occupying the remainder of said frame and extending beyond said frame to provide a protecting flap, rigid triangular 90 frames connected to opposite vertical edges of said frame and disposed at right angles thereto, foraminous material within said triangular frames, and supporting members connected to said triangular frames and to 95 each other and each disposed in the same plane as the corresponding triangular frame.

In testimony whereof I have signed my name to this specification in the presence of two subscribing witnesses.

EDOARDO FERRARA.
